UNITED STATES PATENT OFFICE.

FRANK R. WEST, OF DETROIT, MICHIGAN, ASSIGNOR TO RICE PRODUCTS INC., OF DETROIT, MICHIGAN, A CORPORATION OF MICHIGAN.

COMPRESSOR STRUCTURE.

Application filed February 16, 1927. Serial No. 168,502.

This invention relates to a compressor structure of the type adapted to be used for mechanical refrigerating systems and has to do particularly with a novel valve structure 5 for controlling the flow of refrigerant.

Heretofore in the refrigeration art, the compression system has been recognized as very efficient and desirable. The compressor itself is one of the main factors in the system, and the efficiency of the compressor is largely dependent upon the structure and operation of the valves. Disk and poppet valves have been generally used in the art, and while they have been recognized as commercially efficient and satisfactory, they have presented many difficulties in that they have required more or less fitting of valves to seats, and when improperly designed they have resulted in warping from heat and pressure, and have also been subject to the fatigue of metal structure together with crystallization and breakage after a period of usage. Probably the most objectionable feature of disk and poppet valves of the prior art has resided in their tendency to produce a resonant valve clicking noise when seating. This clicking noise has been due to inherent vibration or resonance in valve and valve seating structure.

It is the object of the present invention to provide a valve structure which will materially obviate the above mentioned disadvantages. I have found that by providing a valve structure formed of a plurality of thin laminated disks in place of a single disk that it is possible to completely change the period of vibration or resonance whereby to shift the clicking noise, if any, outside the range of audible human hearing.

Another object of the present invention is to provide a valve structure formed of thin laminations whereby to permit an exact conformation of the valve to its seat, and to insure a flexibility and lessening of the shock attendant to valve seating.

In the drawings:

Fig. 1 is a fragmentary vertical longitudinal section taken through a compressor cylinder embodying my novel valve structure, and illustrating the manner of forming the discharge valve of relatively thin laminations.

Fig. 2 is a sectional view similar to Fig. 1 but confined to the valve plate and showing the discharge valve in detail and in cross

section, said valve being slightly modified from the showing in Fig. 1, in that the retaining spring contacts directly with the laminations.

Fig. 3 is a plan view of the valve shown in Fig. 2, the cover plate being partially cut away.

The refrigerating system, and the several parts going into the structure of the compressor therefor, need not be referred to in detail, as practically any standard type of compressor or standard system of refrigeration may be utilized in carrying out my invention. I have, therefore, only illustrated a portion of the compressor sufficient to indicate how my invention may be carried out. The cylinder or cylinder block of the compressor may be generally designated 1, and the piston head therefor as 2. The charge may be drawn into the cylinder in the space beneath the piston head in any desired manner, and on the downward stroke of the piston head 2 the charge is adapted to be drawn in through the piston head and into the space between the piston head and the valve plate 3.

Any suitable valve structure may be provided in the piston head, but in the particular embodiment shown, the piston head 2 is relatively thick and is recessed by drilling suitable holes 4 and cutting the same away to form a series of serrations similar to those shown in Fig. 3. A suitable disk valve 5 is adapted to freely float within the chamber formed by such serrations 4, and a cover plate 6 may be placed in a suitably formed recess whereby to fix the limited movement and maintain the arrangement of such disk valve 5.

The valve plate 3 is also relatively thick and is preferably recessed at substantially its entire thickness to form a suitable seat 7. This seat 7 is almost at the bottom of the valve plate whereby to reduce the clearance volume over the piston to a negligible quantity. The recessed part of the valve plate 3 is formed by a series of semi-circular serrations 8. These semi-circular serrations provide a suitable well, or guide, for the valve which may be designated 9.

This valve 9 is preferably of a standard thickness, say about .02 an inch, but instead of being formed of a simple circular integral plate, it is made up of three or four thinner laminated disks loosely placed one

on top of the other, the total height and strength of the disks remaining practically the same as if a single piece of integral metal were used. These disks 9, going to make up the valve, being of very thin laminations completely shifts the period of vibration and resonance so that the click, if any, is practically inaudible to the human ear. Furthermore, the flexibility of these thin laminations permits of an exact conformation of the valve to the seat 7. Furthermore, I preferably place a thin coat or film of lubricating oil between each two laminations before assembly.

15 I have found that this lubrication is maintained between the laminations at all times, and it is believed that such lubrication is maintained partly because of an accumulation of oil utilized in the oil lubricated compressor.

This cushions the noise, and also tends to accentuate the flexibility of the laminations.

20 A suitable cover plate 10 is utilized for maintaining the valve assembly. This cover plate 10 is secured to the upper side of the valve plate 3, and is provided with suitable apertures 11 for permitting the escape of gases which pass up through the serrations 8. A suitable stop screw and guide pin 12 is positioned in the cover plate 10 and is adapted to guide the coil spring 13 and also serves as a stop for the laminated valve 9. In my preferred form the spring 13 contacts with the laminated valve 9, as shown in Fig. 2, but a plunger may be used between the spring and valve as shown in Fig. 1.

25 The valve plate 3 is preferably a die casting, and the serrations 8 and the valve seat 7, forming the same, are accurate whereby the faces of the serrations 8 form a bearing or guide to permit the laminated valve 9 to freely float against the resistance of the coil spring 13.

30 It will be obvious that by utilizing a relatively thick valve plate, together with a relatively thin valve seat and a laminated but thin valve disk 9 that I have been able to reduce all noises incident to valve operation to a minimum. Furthermore, by utilizing a relatively thick valve plate, and by positioning the valve seat closely adjacent the lower edge thereof, and by utilizing thin laminations which are very flexible and lubricated, that I am able to get practically perfect seating of the valve at all times, and a very high volumetric efficiency. I have operated a valve structure designed in accordance with the structure shown in Figs. 1, 2 and 3 for a period of three months, and have found the same to be practically noiseless and in addition to the reduction of noise I have been able to obtain a volumetric efficiency of from 85 to 89 percent at forty pounds head pressure. It will therefore be seen that by providing a relatively thin laminated disk

valve structure that I have not only made it possible to materially reduce the noise but to materially increase the volumetric efficiency of the compressor, particularly when used in combination with the valve plate and valve seat, as illustrated.

5 It will be understood that my laminated valve structure may be used in practically any type of compressor structure, and it will also be understood that the intake valve 5 may be laminated in a similar manner as the discharge valve 9. The laminations illustrated in Figs. 1 and 2 are somewhat exaggerated due to the size of the drawings, but such laminations are preferably no thicker than the solid metallic valve disks that have been utilized in the past.

10 What I claim is:

1. In a compressor structure for mechanical refrigerating systems, a spring pressed laminated, imperforate valve disk for controlling the flow of refrigerant.

15 2. In a compressor structure for mechanical refrigerating systems, a valve seat forming a part of the compressor structure, a plurality of plain, circular flexible laminated disks loosely placed one on top of the other to form a valve structure, each disk being relatively thin whereby the period of vibration, and resonance of each laminated disk 20 is such as to materially reduce any noise incident to the reciprocation or movement of the valve as a whole.

25 3. In a compressor structure for refrigerating systems, a piston adapted to compress the refrigerant, a relatively thick valve plate positioned adjacent the end of the work stroke of the piston, said valve plate being recessed to provide a thin valve seat adjacent the compression side of the valve plate, and a valve of the imperforate disk type positioned on said seat, said valve being formed of flexible relatively thin laminations whereby 30 to permit exact conformation of the valve to its seat and to increase the volumetric efficiency of the unit.

35 4. In a compressor structure for refrigerating systems, the combination of a relatively thick valve retaining means and a relatively thin valve seat therein, and a plurality of relatively thin imperforate disks 35 freely positioned one upon the other and adapted to seat upon said valve seat, said thin disks forming the valve and said valve retaining means cooperating to materially 40 reduce the noise of the valve operation.

45 5. In a compressor structure for mechanical refrigerating systems, a valve seat and a plurality of relatively thin imperforate, circular disks freely mounted one upon the other to form a valve for the seat.

50 6. In a compressor structure for mechanical refrigeration systems, a valve seat and a small, circular, thin valve member adapted to intermittently strike said seat for control-

ling the flow of refrigerant, said valve member being formed of a plurality of relatively thin flexible disks of the same size and freely positioned one adjacent the other.

5. 7. In a compressor structure for mechanical refrigerating systems, a valve seat, and a valve member adapted to intermittently contact with said seat to control the flow of refrigerant, said valve member being formed 10 of a plurality of disks which are relatively thin compared to standard practice, said disks being freely positioned one upon the other, and a film of oil between each two disks, said film of oil being maintained during the 15 operation of the compressor.

8. In a compressor structure for mechanical refrigerating systems, a valve seat, and a plurality of relatively thin, plain, circular disks freely mounted one upon the other to 20 form a valve for the seat, said plurality of disks cooperating to form a single operating valve approximately .02 of an inch in thickness.

9. In a compressor structure for a mechanical refrigerating system, a valve seat 25 and a relatively small circular valve member

adapted to intermittently strike said seat for controlling the flow of refrigerant, said valve member being formed of a plurality of relatively thin disks, said disks being so thin 30 as to positively shift the period of vibration and resonance of the entire valve structure during its operation.

10. Compressor structure for mechanical refrigerating systems of the type having a 35 relatively thick valve plate, a valve cage extending substantially all the way through said plate but leaving only enough metal to form a relatively thin valve seat adjacent the edge of the plate next the piston, comprising 40 in combination a relatively thin valve mounted on said thin valve seat, said thin valve being formed of a plurality of flexible disks of such thinness as to shift the period of vibration and resonance of the valve, 45 whereby to render the operation of the valve practically inaudible, the large mass of metal in the valve plate absorbing any small noises and vibrations in the thin valve seat.

In testimony whereof I affix my signature.

FRANK R. WEST.
